UNITED STATES PATENT OFFICE.

LOUIS RORIMER, OF CLEVELAND, OHIO, ASSIGNOR TO SIMMONS COMPANY, OF KENOSHA, WISCONSIN, A CORPORATION OF DELAWARE.

DESIGN FOR A BEDSTEAD FRAME.

Application filed May 31, 1921. Serial No. 473,904. Term of patent 7 years.

To all whom it may concern:

Be it known that I, LOUIS RORIMER, a citizen of the United States, residing at Cleveland, in the county of Cuyahoga and State of Ohio, have invented a new, original, and ornamental Design for Bedstead Frames, of which the following is a specification, reference being had to the accompanying drawing part thereof.

The figure is a perspective view of a bed-

stead, showing my new design. An important feature of the said design is the spacing of the grilles at a distance from each other, the space between the grilles being occupied by suitable fillers.

I claim:

The ornamental design for a bedstead frame, as shown and described.

LOUIS RORIMER.
